UNITED STATES PATENT OFFICE.

CHARLES J. JOLY, OF ENNIS, TEXAS.

KNOCKDOWN EXTENSION COVERED WAGON-BED.

1,309,856.

Specification of Letters Patent. Patented July 15, 1919.

Application filed February 5, 1919. Serial No. 275,171.

To all whom it may concern:

Be it known that I, CHARLES J. JOLY, a citizen of the United States of America, residing at Ennis, in the county of Ellis 5 and State of Texas, have invented certain new and useful Improvements in Knock-down Extension Covered Wagon-Beds, of which the following is a specification.

My invention relates to knock-down wagon beds and more particularly to extensible wagon beds for cotton; and the object is to provide a wagon bed which can be extended or made larger as needed for hauling greater loads and which can be made as small as may be required. The advantage 10 is that with small amounts or small loads, the surplus body can be removed so that the wagon will be as light as possible, and when larger loads are to be hauled the sides 15 and ends can be built up. Another object is to provide a top or cover which will answer in any case whether a small load or a large load is to be hauled and which cover is readily detachable and replaceable and 20 which will protect the load from the weather. Other objects and advantages will be fully explained in the following description and the invention will be more particularly pointed out in the claims.

Reference is had to the accompanying drawings which form a part of this application.

Figure 1 is a perspective view of the wagon body assembled. Fig. 2 is a broken 35 vertical section, showing the manner of connecting the side boards and also the manner of connecting the top to the side. Figs. 3 and 4 are perspective views of the two hinge members which connect the top to the side. Fig. 5 is a broken sectional view of the meeting 40 edges of the two members which form the top. Fig. 6 is a perspective view of a spring-bracket keeper for the side braces. Fig. 7 is an edge view of the side braces. Fig. 8 is a plan view of the keeper shown 45 in Fig. 6. Fig. 9 is a side elevation of the side brace on an enlarged scale. Figs. 10 and 11 are perspective views of the detachable side and end connecting keepers. Fig. 50 12 is a broken sectional view, showing the keepers, shown in Figs. 10 and 11, in plan view.

Similar characters of reference are used to indicate the same parts throughout the several views.

The body is made of side boards 1 and end boards 2 of ordinary construction with braces 3 for the bottom 22. The side members 1 and the end members 2 are all detachable. The side boards 1 are connected to each other by keepers or brackets which have male and female joint connections. The bracket 4 is attached to the edge of a board 2 so that the joining member 5 will be in vertical position and the edge of the 60 side member is cored out near the end so that the member 5 will be partly countersunk therein. Two angular bracket members 6 are attached to side boards 1 with the horizontal members countersunk in the 65 boards 1. The horizontal members 7 have openings to receive the male members 5 of brackets 4. Both boards 1 have recesses formed in their meeting faces so that the member 5 will be inclosed therein. The end members 2 will be securely held in place by the bracket keepers and the side members 70 will also be held in place by the keepers.

The side members 1 are further braced by braces 8 and extension braces 9. The braces 8 may be permanently attached to one or more boards 1 and the extension braces consist of two sections hingedly connected to the members 8, as shown in Figs. 7 and 8. 80 When the members 9 are not needed for extending the body of the wagon, they may be 85 swung down by the sides of the members 8 and hang loosely. When the body is to be extended, the members 9 are swung up to the positions shown in Figs. 7 and 8 and held in the extended position by spring clips 90 95 10 which are attached to the top member of the side of the wagon. The clips 10 have lateral wings 11. When the members 9 are swung upwardly, the wings 11 will spring upwardly sufficient to receive the upper ends of the extension members 9 and then snap down on them and hold them in place.

The top members 12 and 13 are detachably connected to the top side boards 14 by 100 hinges composed of bolt holding members 15 and hook members 16. The bolt or pivot members 15 are attached to the top members 14 of the side boards and the hook members

16 are attached to the top members. The top members 12 and 13 are provided with sheet metal covers 17 and 18. The sheet 17 is bent at the edge to form a flange 19 and 5 a hook flange 20 is formed on sheet 18 to catch over the flange 19 for holding the top members together and for preventing rain from entering the wagon body.

Brackets 21 are attached to the braces 8 10 for forming shoulders to brace the extension members 9. Various changes in the sizes, proportions, and construction of the several parts may be made without departing from my invention.

15 What I claim is,—

1. An extension body for wagons having detachable and replaceable side and end boards and keeper brackets attached to the edges of the end boards and provided with 20 male members, coöperating keeper brackets attached to the side boards and provided with female members countersunk in said side boards to receive said male members, and braces for the side boards to prevent 25 lateral spreading consisting of permanent members attached to the lower side boards

and extending members hingedly connected to said permanent members.

2. An extension body for wagons having detachable side and end boards, keeper brackets attached to the edges of said end boards and provided with male members, angular brackets attached to said side boards and having horizontal members projecting between the meeting edges of the side boards 3 and provided with recesses to receive the male members of the end brackets, and extension braces attached to said side boards for preventing lateral spreading of the side boards.

3. A knock down wagon body having removable and replaceable side and end boards detachably connected together and extension braces for the side boards consisting of permanent members attached to the lower 40 side boards and extension members hingedly connected to said permanent members and spring clips for holding said extension members in place.

In testimony whereof, I set my hand, this 50 5th day of Dec., 1918.

CHARLES J. JOLY.
